UNITED STATES PATENT OFFICE.

ROBERT E. McELDONNEY, OF NEW MARTINSVILLE, WEST VIRGINIA, ASSIGNOR TO
NEW MARTINSVILLE GLASS MFG. CO., OF NEW MARTINSVILLE, WEST VIRGINIA,
A CORPORATION OF WEST VIRGINIA.

VANITY SET.

Application filed November 20, 1926. Serial No. 149,581.

My invention relates to a new and useful vanity set or three piece container and it consists more particularly in a novel container adapted to be used for the reception 5 of toilet articles and boudoir accessories, such as powder, rouge, lipstick, perfume and the like.

My invention further relates to a novel container of the general character described 10 and commonly known as "vanity set" or "compact", whereby ladies' toilet or "make up" materials may be kept in a single, compact, unitary receptacle, the different accessories, however, being contained in different 15 individual compartments, which are normally closed, but at all times readily accessible.

My invention still further resides in a container in which ladies' toilet articles may be kept in tightly closed, sanitary compartments 20 and yet be readily accessible for use at all times.

It has frequently been the practice heretofore, to provide a separate box for powder, and another for rouge, while perfume 25 was kept in a separate bottle. The lipstick was tossed around on the tip of the "dresser" or casually placed in one of the drawers. This practice, not only resulted in frequent 30 confusion and loss of time due to misplacing or mislaying one or the other of these toilet articles, but also resulted in an untidy appearance of the vanity dressing table, because of the multiplicity and heterogeneous character of the receptacles employed.

It is the object of my invention to obviate 35 these disadvantages by providing a single, compact, unitary container or vanity set in which such toilet articles may be readily accessible, thus not only eliminating the risk 40 of misplacement or loss of such articles, but also greatly reducing the number of receptacles and containers heretofore employed, thereby giving the vanity dressing table a neat and tidy appearance.

Another object of my invention is to produce 45 a container of this character, which, in addition to being compact and efficient, will also be highly artistic, attractive and ornamental.

For the purpose of illustrating my invention, I have shown, in the accompanying drawings, a form thereof, which is at present preferred by me, since it will give in practice, satisfactory and reliable results, al-

though it is to be understood, that the various instrumentalities of which my invention consists can be variously arranged and organized and that my invention is not limited to the precise arrangement and organization of these instrumentalities as herein shown and described.

In the accompanying drawings:

Figure 1 represents, in detached position, a perspective view of the different elements 65 composing my novel construction.

Figure 2 represents a vertical sectional view of my novel vanity set in assembled position.

Figure 3 represents a top plan view of the lowermost compartment, shown in detached 70 position.

Figure 4 represents a bottom plan view of the uppermost combined lid and compartment.

Referring to the drawings, in which like 75 reference characters indicate like parts, 1 designates the lowermost or base member of my novel container or vanity set, comprising the bottom or base 2, and the annular vertical wall 3. 4 designates a cup or 80 receptacle, open at its top and preferably centrally disposed with respect to, and formed integrally with said base 2 and adapted to be used for the reception of rouge. 5 designates a transverse trough or 85 concave depression in which the lipstick may be placed. The space around said receptacle or cup 4 and said trough 5, in said lower compartment 1, may be utilized for keeping pins and other similar toilet accessories. 6 designates a middle or intermediate compartment, comprising the annular, vertical wall 7 and the bottom or base 8, provided with the pendant annular shoulder or male counterbore 9 of a diameter 90 slightly smaller than the diameter of the upper rim of the lower compartment 1 and adapted to seat therein as will be understood from Figure 2. 10 designates the combined lid or cover and uppermost compartment 100 consisting of the body portion 11 terminating in the pendant annular flange 12 of a diameter adapted snugly to fit into the upper rim of the middle compartment 6, directly below it, as will be understood from 105 Figure 2. 13 designates a bottle shaped chamber or reservoir for the reception of perfume, toilet water or the like, said reser-

voir 13 terminating at its upper end in the neck 14 in which is fitted the stopper 15, while the bottom of said reservoir may be substantially flush with the plane of the rim 5 of the middle compartment 6 thus not in any way interfering with the contents of such compartment.

A plurality of the middle or intermediate sections or compartments 6 may be employed, since each of such compartments may serve as a base for the compartment superimposed thereon, as well as a lid or closure for the compartment on which it is superimposed, and also the shape or contour of said sections 1, 6 and 10, and said trough 5 and reservoir 13, may be varied and modified to suit different requirements.

It will thus be apparent that I have devised a novel container which is adapted for 20 simultaneously receiving and containing different articles in a sanitary and readily accessible manner, and one which is compact, economical, efficient and ornamental in appearance. The base member can obviously be cheaply cast or moulded out of 25 glass or the like, as an integral structure, as can also the intermediate and top members.

It will now be apparent that I have devised a novel and useful vanity set which 30 embodies all the features of advantage enumerated as desirable in the statement of the invention and the above description, and while I have, in the present instance, shown and described a preferred embodiment 35 thereof, which will give in practice, satisfactory and reliable results, it is to be understood that such embodiment is susceptible of modification in various particulars

without departing from scope of my invention or sacrificing any of its advantages. 40

Having thus described my invention, what I claim as new, and desire to secure by Letters Patent is:—

1. In a container of the character stated, a bottom compartment having a central cup 45 and a transverse trough, an intermediate compartment superimposed thereon and vertically aligning therewith, a lid covering said intermediate compartment, a bottle-like receptacle formed integral with and depending from said lid, the vertical axes of 50 said bottle-like receptacle and said central cup being in alignment, means for maintaining said parts in vertical alignment, and a stopper for said bottle-like receptacle. 55

2. In a device of the character stated, a bottom compartment, having a central cup and a transverse trough cast therein, an intermediate compartment superimposed thereon and vertically aligning therewith, a lid 60 for said intermediate compartment, the lower periphery of said cover and said intermediate compartment being provided with an annular pendant male counterbore, 65 adapted to engage the rim of said intermediate compartment and said bottom compartment respectively, thereby to maintain said lid and said intermediate compartment in vertical alignment with respect to each other and said bottom compartment, a bottle-like receptacle formed integral with said lid and depending therefrom, the vertical axes of 70 said bottle-like receptacle and said central cup being in alignment, and a stopper for said bottle-like receptacle. 75

ROBERT E. McELDOWNEY.
